UNITED STATES PATENT OFFICE.

GEORGE A. LOWRY, OF CHICAGO, ILLINOIS, ASSIGNOR, BY DIRECT AND MESNE ASSIGNMENTS, TO THE PLANTERS COMPRESS COMPANY, OF WEST VIRGINIA.

PRESS FOR COTTON, WOOL, &c.

SPECIFICATION forming part of Letters Patent No. 630,370, dated August 8, 1899.

Application filed March 1, 1897. Renewed January 6, 1899. Serial No. 701,411. (No model.)

To all whom it may concern:

Be it known that I, GEORGE A. LOWRY, a citizen of the United States, residing at Chicago, in the county of Cook and State of Illinois, have invented a new and useful Improvement in Presses for Cotton, Wool, and the Like, of which the following is a specification.

This invention relates to presses for cotton, wool, hair, hay, and the like.

10 The object of the invention is to provide a press of novel and exceedingly simple construction for pressing cotton, wool, hair, and the like into bales.

15 A further object of the invention is to provide means for absorbing the heat generated during the operation of pressing.

A further object of the invention is to provide means for facilitating the delivery of the material to the press.

20 Other objects of the invention will appear more fully hereinafter.

The invention consists, substantially, in the construction, combination, location, and relative arrangement of parts, all as will be more 25 fully hereinafter set forth, as shown in the accompanying drawings, and finally more specifically pointed out in the appended claims.

Referring to the accompanying drawings and the various views and reference-signs appearing thereon, Figure 1 is a view in central longitudinal section of a press embodying the principles of my invention. Fig. 2 is a plan view of the cap-plate, a portion being in horizontal section, illustrating the slots through 35 which the material is to be delivered to the press. Fig. 3 is a side elevation of the cap-plate. Fig. 4 is a broken detail sectional view of the cap-plate on the line 4 4, Figs. 1 and 2. Fig. 5 is a view similar to Fig. 2, showing 40 means for exhausting the air from the feed slots or openings in the cap-plate, thereby creating a suction for facilitating the delivery of the material to be pressed therethrough. Fig. 6 is a central transverse sectional view of the 45 construction shown in Fig. 5 on the line 6 6, looking in the direction of the arrows. Fig. 7 is a broken detail sectional view on the line 7 7, Fig. 6, looking in the direction of the arrow.

The same part is designated by the same 50 reference-sign wherever it occurs throughout the drawings.

I have shown my invention as applied to the type of press set forth and fully described and claimed in my Patents Nos. 581,600 and 55 581,601, dated April 29, 1897, and wherein is shown and described a type of press comprising an open-ended chamber A and a cap-plate B for one end thereof, said chamber and cap-plate being mounted for relative rotation. 60 For instance, in the particular form shown the chamber A is rotated through suitable gearing, while the cap-plate B is rigidly mounted upon the casing C. Any suitable gearing for relatively rotating the chamber and the 65 cap-plate may be provided, as set forth in my prior invention.

Inasmuch as the present invention relates more particularly to the construction and arrangement of the cap-plate, I do not deem it 70 necessary herein to specifically set forth the construction and arrangement of the other parts of the press.

In the operation of a press embodying the principles of my invention, and particularly 75 of the type set forth in my before-mentioned patents, wherein the material to be pressed is subjected to pressure, a considerable degree of heat is developed by reason of the friction of the material against the under surface of 80 the cap-plate during the relative rotations of the chamber and cap-plate. In order to avoid excessive heating from this cause, I construct in my present invention the cap-plate B, with a raised peripheral rim or flange D, thereby 85 forming a receptacle in the top surface of the cap-plate, as indicated at E, adapted to receive water or other cooling agent, a circulation of which, if desired, may be maintained through such receptacle or chamber E, and, if 90 desired, an overflow-opening F may be provided, whereby such circulation may be maintained, as shown in Fig. 1. By this construction I avoid the objection of excessive heat due to friction developed during the operation of the machine. 95

I will now describe the construction of the cap-plate, whereby the delivery of the ma-

2
material to be pressed therethrough to the chamber A is facilitated.

In my before-mentioned patents I have shown a cap-plate provided with a single slot or opening therethrough and through which the material to be pressed is introduced to the press-chamber. In some cases, however, it may be desirable—for instance, in the case employing my press as a cotton-press—to deliver into the press-chamber A from a plurality of gins simultaneously. In such case it may be desirable to deliver the product of the plurality of gins through several slots or openings in the cap in order to expedite the operation of turning out bales from the press. In order to accommodate the press, therefore, to a bank of several gins, whereby the speed of the pressing operation is accelerated by supplying to the press the product from several gins simultaneously, and in order to facilitate the feed of the material through the cap-plate, I provide said cap with a plurality of passages G, into each of which one or more gins may deliver and each of which in turn opens into the pressing-chamber A in a manner similar to the opening through the cap-plate in my prior application. Thus it will be seen that I provide a construction of cap adapting each press to be supplied from a bank of several gins simultaneously, and since the speed of compression of the bale is dependent more or less upon the rapidity of feed of material to the press it will be seen that I provide a construction wherein the work of effecting a compression of the material into bale form is accomplished rapidly and efficiently.

It is a common practice to deliver the lint-cotton from gins by means of a forced air-blast. If, however, such blast delivered the lint cotton into a closed chamber—such, for instance, as the passages G of the cap-plate—the efficiency of the delivery of the material to be pressed to the chamber A is materially decreased by reason of the fact that such air is not provided with an outlet. In order to remove this objection and to provide an arrangement wherein the lint cotton is relieved of the pressure of the forced draft within the passages G, whereby the material to be pressed may be efficiently delivered through the delivery mouth or opening of such passages, I provide suitable openings H J through the walls of such passages G, through which the forced air-blast of the gin-feed may readily escape. In order to increase the efficiency of the delivery of the material through the passages G, I may, if desired, attach a suitable fan to the connections K, which communicate with the openings H J, whereby a suction or eduction is created through the openings H J, thereby drawing through such openings the air of the gin blast-feed, which tends to create a vacuum within the passages G, whereby the material is drawn through the passages G to the delivery end of such passages. In order to make this feature of

my invention effective for drawing the material to the delivery end of the passage G, I arrange said openings H J or one of them in as close proximity to such delivery end of the passage as may be possible, as clearly shown, whereby the cotton is drawn as nearly as possible to the point of delivery to the pressing-chamber, and hence, if desired, I may omit the openings H J. In order to prevent the material delivered to the press from being drawn through the openings H J and connections K, I arrange a suitable gauze or netting over said openings, as clearly shown.

While the features of my invention, as above explained, are applicable to any suitable or desirable construction of cap-plate, I have shown said features applying to a cap-plate wherein the inner side thereof—that is, the side thereof which projects into the open end of chamber A—is provided with a surface which projects to an increasing depth into the chamber, as more particularly set forth in my before-mentioned application, and whereby the feed of the material is facilitated by reason of the fact that the delivery-mouth of passage G is formed of two lips, one of which—namely, the inner lip L—operates in the lower plane, and the point of the other or far lip is at M, Figs. 4 and 7.

In order that the material may be delivered to the chamber at a point in line with the inner surface of such chamber, I preferably form a peripheral groove in the upper inner edge of the chamber, as indicated at N, Fig. 1, and I extend the portion of the cap-plate which fits over the open end of the chamber to a point enabling it to enter or be received in the groove N, as clearly shown in Fig. 1, whereby the outer edge of the passage G delivers into the chamber at least in line with or outside of the inner surface of the end of the chamber. Thus the material is delivered to the chamber at a point such that it will engage or ride against the inner wall of the chamber from the time it is delivered to the machine. This I have found to be a beneficial feature, for the reason that in the case of rotating the chamber A instead of the cap-plate the holding of the mass of material contained in the chamber stationary during the rotation of such chamber is avoided.

Many variations and changes in the details of construction, location, and arrangement of parts would readily suggest themselves to persons skilled in the art and still fall within the spirit and scope of my invention. I do not desire, therefore, to be limited or restricted to the exact details of construction and arrangement shown and described; but,

Having now set forth the object and nature of my invention and a form of apparatus embodying the same and having explained the construction, function, and mode of operation thereof, what I claim as new and useful and of my own invention, and desire to secure by Letters Patent, is—

1. In a cotton or other press, an open-ended

receiving-chamber, a slotted cap-plate for one end of said chamber, in combination with a suction-feed arranged to deliver the material to be pressed through the slot in said cap-plate and into said chamber, and means for relatively rotating said chamber and cap-plate whereby such material is subject to progressive pressure, as and for the purpose set forth.

10 2. In a cotton or other press, an open-ended receiving-chamber contracting in internal diameter from one end toward the other, a cap-plate therefor, an opening through such cap-plate, through which the material is delivered to said chamber, means for creating a suction adjacent to the delivery end of such opening, and means for relatively rotating said cap and chamber, as and for the purpose set forth.

3. In a cotton or other press, a receiving-chamber, a cap-plate therefor provided with a feed-opening, a passage formed in said cap-plate and communicating with the feed-opening, means for creating an air-draft through said passage and means for relatively rotating said cap and chamber, as and for the purpose set forth.

4. In a cotton or other press, a receiving-chamber, a cap-plate therefor, provided with a feed-opening, said cap-plate arranged to project to a progressively-increasing depth into said chamber, a passage formed in said cap-plate and communicating with the feed-opening in said cap-plate, means for creating an air-draft through said passage and means for relatively rotating said cap-plate and chamber, as and for the purpose set forth.

5. In a cotton or other press, an open-ended receiving-chamber contracting in internal diameter from one end toward the other, a cap for one end of such chamber, said cap provided with a series of slots or openings through which the material is delivered into the chamber, and means for relatively rotating said chamber and cap, as and for the purpose set forth.

45 6. In a cotton or other press, a receiving-chamber, a cap for one end of such chamber, the inner surface of such cap arranged to pro-

ject to successively-increasing distances into said chamber, and having a series of slots or openings through which the material is introduced to the chamber, and means for relatively rotating said chamber and cap, as and for the purpose set forth.

7. In a cotton or other press, a chamber, a cap therefor through which the material to be pressed is delivered to the chamber, means for relatively rotating said chamber and cap, and means for maintaining said cap cooled, as and for the purpose set forth.

15 8. In a cotton or other press, a chamber, a cap therefor through which the material to be pressed is delivered to the chamber, means for relatively rotating said chamber and cap, and means for absorbing the heat generated during the pressing operation, as and for the purpose set forth.

9. In a cotton or other press, a chamber, a cap therefor through which the material to be pressed is delivered to the chamber, said cap provided with a peripheral flange thereby forming a receptacle through which a cooling medium may be circulated, and means for relatively rotating said chamber and cap, as and for the purpose set forth.

20 10. In a cotton or other press, a chamber, a cap therefor through which the material to be pressed is delivered to the chamber, means for relatively rotating said chamber and cap, and a water-jacket for such cap, as and for the purpose set forth.

25 11. In a cotton or other press, a chamber, a cap therefor provided with a slot or opening through which the material to be pressed is delivered to said chamber, the chamber provided with a peripheral groove in the end thereof adapted to receive said cap, and means for relatively rotating said cap and chamber, as and for the purpose set forth.

30 In witness whereof I have hereunto set my hand, this 26th day of February, 1897, in the presence of the subscribing witnesses.

GEORGE A. LOWRY.
